(57) **CLAIM**

The ornamental design for a dispensing valve, as shown and described.

DESCRIPTION

FIG. 1 is an isometric view of a dispensing valve showing the design.

FIG. 2 is a side elevation view of the dispensing valve of FIG. 1.

FIG. 3 is another side elevation view of the dispensing valve of FIG. 1.

FIG. 4 is another side elevation view of the dispensing valve of FIG. 1.

FIG. 5 is another side elevation view of the dispensing valve of FIG. 1.

FIG. 6 is a top plan view of the dispensing valve of FIG. 1.

FIG. 7 is a bottom plan view of the dispensing valve of FIG. 1; and,

FIG. 8 is another isometric view of the dispensing valve of FIG. 1.

The dashed broken lines shown in the drawings depict portions of the dispensing valve that form no part of the claim. The shading lines shown in the drawings represent the contour and are not intended to represent surface decoration.
